UNITED STATES PATENT OFFICE

WILHELM A. A. H. HELWIG, OF DETROIT, MICHIGAN, ASSIGNOR OF ONE-THIRD TO
SAM DICKMAN, OF DETROIT, MICHIGAN

VENTILATING PORT

Application filed July 26, 1929. Serial No. 381,292.

This invention relates to ports for ships, and the object thereof is to provide an improved port which will admit air, but not water, therethrough.

More specifically, the present invention aims to provide an improved port so constructed that the dashing of the waves against the port, or the submersion of the port by the rolling of the ship will assist in forcing air through the port into the ship.

Another object is to provide a port wherein the movement of the latter out of and above the surface of the sea will permit draining of water from the port into the sea so as to suck foul air through the port from the ship.

The invention consists in the novel form, combination and arrangement of parts hereinafter more fully described, shown in the accompanying drawings, and claimed.

In the drawings:

Figure 1 is a fragmentary side elevation of a ship provided with a port embodying the present invention, looking at the outer side of the port.

Figure 2 is a similar view looking at the inner side of the port.

Figure 3 is an enlarged section on line 3—3 of Figure 1.

Figure 4 is a section on line 4—4 of Figure 3; and

Figure 5 is a top plan view of the glass-carrying frame of the port.

Referring more in detail to the drawings, the hull of the ship is provided with spaced walls 5 and 6 formed above the normal water line with aligned openings in which is fixed a port hole casing 7 having oval-shaped openings 8 through the top thereof. Hinged to the casing 7 is a frame 9 carrying three spaced glasses 10, 11 and 12 and provided with oval openings 13 at the top adapted to register with the openings 8 when the frame is closed. The glass 11 divides the frame 9 into two chambers which, directly, are non-communicating. As the glass 11 is imperforate and has a waterproof fitting in the frame 9, the water may not find passage by the same into the ship.

Arranged vertically between the walls 5 and 6 above the port hole is an inverted U-

shaped pipe 14, having flattened ends 15 fitted tightly in the openings 8 of frame 7, and providing communication between the chambers in the frame 9 at opposite sides of the glass 11. The outer glass 12 has its lower portion cut away at 16 and is formed with a central opening 17, while the inner glass 10 is cut away at the top and bottom as at 18 and 19. The pipe 14 is of a length to lead well above the water line of the ship's hull.

In operation, water will enter through the opening 17 and cut out 16 and rise in the outer leg of pipe 14, thus forcing the fresh air ahead of the same through the inner leg of pipe 14 and from the inner chamber of the port

through cut outs 18 and 19 into the ship. The fall of the water in the outer leg of pipe 14 sucks foul air from the ship through the cut outs 18 and 19 and the outer chamber of the port into the pipe 14, and when the water

drains from the outer leg of pipe 14 and the outer chamber of the port through opening 17 and cut out 16 into the sea, this foul air is drawn entirely out of the ship. Due to the length of the pipe 14, no water will rise to the top bend of said pipe and passage of water

into the ship is prevented without the use of objectionable check valves or the like. The arrangement of the opening 17 and cut outs 16, 18 and 19 insures proper admission of air ahead of the water, ready exit and entrance of the air and water at the glasses 10 and 12, and unobstructed vision through the port hole. Moreover, the pipe 14 does not interfere with opening and closing of the frame 9, while the construction is simple and durable, efficient in use, and capable of ready installation.

Minor changes are contemplated within the spirit and scope of the invention as claimed.

What I claim as new is:

1. In a ventilated port for ships, a casing having a pair of top openings, an inverted U-shaped pipe vertically disposed above said casing and having its ends fitted in said openings, a frame in the casing having top openings aligned with the respective openings of the casing, and a glass in said frame on a plane between the openings thereof to pre-

vent the passage of water directly through said frame.

2. In a ventilated port for ships, a casing having a pair of top openings, an inverted U-shaped pipe vertically disposed above said casing and having its ends fitted in said openings, a frame in the casing having top openings alined with the respective openings of the casing, and a glass in said frame on a plane between the openings thereof to prevent the passage of water directly through said frame, and further glasses in the frame spaced from the inner and outer sides of the first-named glass and cut away for permitting flow of air past the same into and out of said frame.

3. In a ventilated port for ships, a casing having a pair of top openings, an inverted U-shaped pipe vertically disposed above said casing and having its ends fitted in said openings, a frame in the casing having top openings alined with the respective openings of the casing, and a glass in said frame on a plane between the openings thereof to prevent the passage of water directly through said frame, and further glasses in the frame spaced from the inner and outer sides of the first-named glass and cut away for permitting flow of air past the same into and out of said frame, said frame being hinged to the casing, the second named glasses being cut away at the bottom thereof.

4. In a ventilated port for ships, a casing having a pair of top openings, an inverted U-shaped pipe vertically disposed above said casing and having its ends fitted in said openings, a frame in the casing having top openings alined with the respective openings of the casing, and a glass in said frame on a plane between the openings thereof to prevent the passage of water directly through said frame, and further glasses in the frame spaced from the inner and outer sides of the first-named glass and cut away for permitting flow of air past the same into and out of said frame, said frame being hinged to the casing, the second named glasses being cut away at the bottom thereof, the outer glass further having a central opening, and the inner glass being further cut away at the top.

5. A ship provided with a hull composed of spaced walls formed with alined port holes, a casing for said holes provided with top openings, an inverted U-shaped pipe arranged vertically between said walls above the casing and extending well above the water line of the hull, the ends of said pipe being fitted in the openings of the casing, a frame mounted in the casing and having top openings registered with the top openings of the casing, and a glass in the frame on a plane between its top openings to prevent passage of water directly through said frame.

6. A ship provided with a hull composed of spaced walls formed with alined port holes, a casing for said holes provided with top

openings, an inverted U-shaped pipe arranged vertically between said walls above the casing and extending well above the water line of the hull, the ends of said pipe being fitted in the openings of the casing, a frame mounted in the casing and having top openings registered with the top openings of the casing, and a glass in the frame on a plane between its top openings to prevent passage of water directly through said frame, and further glasses in the frame spaced from the inner and outer sides of the first-named glass and cut away for permitting flow of air past the same into and out of said frame.

In testimony whereof I affix my signature. so
WILHELM A. A. H. HELWIG.
